[57] CLAIM

The ornamental design for a transaction system console, as shown and described.

DESCRIPTION

FIG. 1 is an enlarged perspective view of a transaction system console showing our new design;

FIG. 2 is a top plan view thereof;

FIG. 3 is a right side elevational view thereof, the left side is identical in appearance; the keys are shown in broken lines for illustrative purposes only in FIG. 3 and form no part of the claim's design; and,

FIG. 4 is a front elevational view thereof.

The rear side of the illustrated transaction system console is unornamented.

FIG. 1

FIG. 2

FIG. 4

FIG. 3
